UNITED STATES PATENT OFFICE.

ABBOTT L. WRIGHT, OF CHICAGO, ILLINOIS.

AIR-BRAKE ATTACHMENT.

1,238,375.

Specification of Letters Patent. Patented Aug. 28, 1917.

Application filed September 22, 1915. Serial No. 51,947.

To all whom it may concern:

Be it known that I, ABBOTT L. WRIGHT, a citizen of the United States, residing at Chicago, in the county of Cook and State of Illinois, have invented certain new and useful Improvements in Air-Brake Attachments, of which the following is a specification.

My invention relates to an attachment for use in connection with an air-brake system, and refers particularly to a readily portable device which may be connected with the air-brake system of one or more cars when desired.

My invention is particularly useful for the gravity switching of freight cars, although it may be advantageously employed in any circumstances in which it is desired to operate the air-brake system of one or 20 more cars when a locomotive carrying the usual air-pump and main reservoir is not connected with such cars.

It is the object of my invention to provide means by which the air-brake system 25 of a car or a series of connected cars isolated from a locomotive may be readily operated so that the cars may at all times be under the superior control which is afforded by air-brakes in distinction to hand-operated 30 brakes.

One of the greatest advantages of my invention is in connection with the gravity switching of freight cars. According to the practice which has heretofore been employed, when a car has been sent over the "hump" of the gravity switch a brakeman stationed on top of the car has controlled the brake system of the latter solely by means of the hand-operated mechanism connected with the brakes. This entails great labor on the part of the brakeman and the control has been very imperfect resulting in many cases in violent collisions between cars and consequent danger to the brakeman. 40 In cold weather when the cars have been covered with ice these conditions have been aggravated to such an extent that it has been impossible to operate the gravity system of switching.

By the provisions of my invention compressed air may be supplied to the train pipe of the car from a readily portable device, which consists, in brief, of a high-pressure reservoir which serves to charge a low-pressure reservoir, which, in turn, may be brought into communication with the train

pipe upon suitable operation of a brake-valve. In this way the car is at all times under the perfect and easy control of the brakeman, who is not obliged to encounter 60 the great risks attendant upon hand-braking, and by means of which violent collisions between cars, with consequent damage to the cars and their contents, are avoided.

These and other advantages of my invention will be more readily understood by reference to the accompanying drawings, which show a preferred embodiment of my invention, and in which—

Figure 1 is a front elevation of my improved air-brake attachment;

Fig. 2 is a side elevation and partial sectional view of the attachment shown in Fig. 1; and

Fig. 3 is an end elevation of a freight car, 75 showing my attachment as applied thereto.

The high-pressure reservoir 10 is provided at its end with the automatically acting valve 11 through which the reservoir may be charged with air to any convenient pressure, as, for example, three to four hundred pounds. Extending from the opposite end of the high-pressure reservoir 10 is the pipe 12, which communicates with the low-pressure reservoir 13, a pressure-reducing valve 80 14 being located in the pipe 12. The pressure-reducing valve 14 is set to admit air to the low-pressure reservoir 13 only up to a predetermined maximum, this maximum ordinarily being approximately seventy 85 pounds. The hanger rod 15 is attached to the high-pressure reservoir 10 and the low-pressure reservoir 13 by means of the straps 16 so that these reservoirs are firmly attached to each other. The lower end of the 90 hanger rod 15 is preferably bent around the lower edge of the low-pressure reservoir 13, as clearly shown in Fig. 2, and its upper end is provided with the hook 17 by means of which the air-brake attachment may be 95 supported from one of the rungs 18 of the usual ladder 19 located at the end of a car 20.

The pipe 21 leads from the low-pressure reservoir 13 to the brake-valve 22 controlled 105 by the brake-handle 23. In pipe 21 is placed the safety-valve 24, which is set to allow air to escape when the pressure within the low-pressure reservoir 13 exceeds the predetermined maximum, and thus acts as a safety 110 device if the reducing-valve 14 should fail to operate. The pipe 25 leads from the

brake-valve 22 to the elbow member 26, which is preferably provided with a threaded end 27 by which it is attached to the boss 28 on the lower end of the low-pressure reservoir 13. The flexible pipe 29, of rubber or the like, leads to the coupling member 30, which may be readily attached to the coupling member 31 carried by the air-brake hose 32 of the car 20, this air-brake 10 hose 32 being in direct communication with the train pipe, of well-known construction.

A pipe 33 leads from the high-pressure reservoir 10 to the duplex pressure gage 34, and the pipe 35 also leads from the pipe 15 25 to the duplex pressure gage. The gage 34 has a pair of indicating hands 36 and 37, one of which, as, for example, 36, indicates the pressure within the pipe 33, and thus within the high-pressure reservoir 10, and 20 the other of which, as, for example, 37, indicates the pressure within the pipe 35, and thus within the pipe 25 and the train pipe with which the pipe 25 is connected.

The pipes 21 and 25 are preferably provided with the valves 38 and 39, respectively, which may be closed when my air-brake attachment is not in use in order to prevent leakage if the brake-valve 22 should be accidentally moved.

30 The brake-valve 22 may be operated by means of its handle 23 in order to assume three significant positions, which will be designated as "A", "B" and "C", respectively. In position "A" the brake-valve establishes communication between the pipes 21 and 25. In position "B" communication between pipes 21 and 25 is interrupted, but communication between pipe 25 and the atmosphere is established through the aperture 40. In position "C" communication between pipes 21 and 25 and between either of these pipes and the atmosphere is interrupted. The latter position is what is ordinarily known as the 'lap' position.

45 Having thus described the various parts used in connection with my invention, the operation of the same may readily be understood: When it is desired to operate one car or a series of connected cars, the attachment is hung on one of the cars, as, for example, by applying the hook 17 to one of the rungs 18 of the ladder 19, as indicated in Fig. 3. The couplings 30 and 31 are connected, and communication is thereby established from the pipe 25 to the train pipe, which, of course, is closed at the opposite end of the car or series of connected cars. The indicating hand 37 of the duplex pressure gage 34 will indicate the pressure 50 of air in the train pipe, and if this pressure is too low the brake-valve is moved to position "A", whereupon air flows from low-pressure reservoir 13 through pipes 21, 25 and 29 to the train pipe, thereby increasing 60 the pressure within the latter to the de-

sired amount, and thus causing the auxiliary reservoir on the car to be charged and releasing the brakes.

When it is desired to make an application of the brakes, the brake-valve is moved 70 to position "B", whereby air flows from the train pipe through pipes 29 and 25 and aperture 40 to the atmosphere, thus reducing the pressure in the train pipe and causing the triple-valve to operate to cause air 75 to flow from the auxiliary reservoir to the brake cylinder to apply the brakes. I prefer to have the aperture 40 in the brake-valve comparatively small in order to avoid too sudden application of the brakes which might result from operation of my attachment by a comparatively unskilled brakeman. When it is desired to hold the brakes in the position to which they have been moved, the brake-valve is held in position 80 "C", which, as previously explained, is the "lap" or neutral position.

When air is allowed to flow from the low-pressure cylinder 13 to the train pipe, as just described, the pressure in this reservoir is maintained by the flow of air from the high-pressure cylinder 10 to the low-pressure cylinder 13 through the pipe 12 and reducing-valve 14. When the pressure within the high-pressure cylinder 10 has 95 been reduced so that it approaches the normal pressure within the low-pressure reservoir 13, the high-pressure reservoir 10 is recharged from a suitable source of compressed air.

100 It will be apparent that by means of my invention the air-brake system of one or more cars may be quickly and easily controlled, and that many changes could be made in the detailed construction of the 105 various parts which I have described without departing from the spirit or scope of my invention, as defined in the appended claims.

What I claim is:

1. An air-brake attachment, comprising 110 a unitary structure consisting of a reservoir adapted to contain air under pressure, means for removably supporting said reservoir on a car, means carried by said reservoir for connecting said reservoir with a train pipe, and a brake-valve in said connecting means.

2. An air-brake attachment, comprising 115 the combination of a high-pressure reservoir, a low-pressure reservoir communicating with said high-pressure reservoir, means for mechanically supporting said low-pressure reservoir on said high-pressure reservoir, means for connecting said low-pressure reservoir with a train pipe, a brake-valve in said connecting means, and means for removably supporting said attachment 120 on a car.

3. An air-brake attachment, comprising 125 the combination of a high-pressure reser-

voir, a low-pressure reservoir communicating with said high-pressure reservoir, a reducing-valve between said high and low-pressure reservoirs, means for connecting 5 said low-pressure reservoir with a train pipe, and a hook for removably suspending said attachment on a car.

4. In an air-brake attachment, a unitary structure comprising the combination with 10 a high-pressure reservoir, of a low-pressure reservoir communicating with said high-pressure reservoir, means for mechanically supporting said low-pressure reservoir on said high-pressure reservoir, a pressure-reducing valve between said high-pressure and low-pressure reservoirs, a brake-valve, means connecting said low-pressure reservoir with said brake-valve, means for connecting 15 said brake-valve with a train pipe, a safety valve in the means connecting said low-pressure reservoir and said brake-valve, a duplex pressure gage, means connecting said pressure gage with said high-pressure reservoir, means connecting 20 said pressure gage with the means for connecting said brake-valve with the train pipe, and means

for removably supporting said attachment on a car.

5. An air-brake attachment, comprising the combination of a high-pressure reservoir, 30 a low-pressure reservoir communicating with said high-pressure reservoir, a brake-valve, means connecting said brake-valve with said low-pressure reservoir, an elbow carried by one of said reservoirs, 35 means connecting said brake-valve with said elbow, and a flexible pipe carried by said elbow and adapted to be connected with a train pipe,

6. An air-brake attachment, comprising 40 a unitary structure consisting of a reservoir adapted to contain air under pressure, means carried by said reservoir for connecting the same with a train pipe, a brake valve in said connecting means, and a hook 45 for removably suspending said attachment on a car.

In witness whereof, I hereunto subscribe my name this 20th day of September, A. D., 1915.

ABBOTT L. WRIGHT.
